CONTROL APPARATUS FOR ELECTRIC LOCKS FOR RAILWAY TRACK SWITCHES

Harold J. Brown, Trafford, Pa., assignor to Westinghouse
Air Brake Company, a corporation of Pennsylvania

Application December 12, 1950, Serial No. 200,483

7 Claims. (Cl. 246—146)

My invention relates to control apparatus for electric locks for railway track switches. More specifically, my invention relates to an arrangement for so controlling an electric lock for a railway track switch, which connects a main railway track with an auxiliary railway track, that the switch cannot be returned from its reverse or auxiliary track position to its normal or main track position unless an associated derail for the auxiliary track is returned to the normal or derailing position.

Operation of a railway track switch may be effected from a central or a distant point such, for example, as an interlocking tower or a dispatcher's office, or it may be effected locally. Operation of a railway track switch which is effected locally is usually accomplished by manual power applied through a manually operable switch operating lever direct to suitable mechanism for moving the switch between normal and reverse extreme positions.

Manually operable switch operating levers are equipped with padlocks in order to prevent movement of the switches by unauthorized persons. However, a railroad employee who has a switch padlock key might become confused or might misunderstand or forget an order or timetable regulation, and might therefore open a switch padlock and move the associated switch while it is unsafe to do so. If, for example, a trainman should erroneously reverse a switch for a train to move from an auxiliary track when a train is approaching at high speed on a main track in which the switch is located, there would probably be a collision between the two trains.

In order to protect against manual operation of a railway track switch while traffic conditions are such that it is unsafe for the switch to be operated, an electric lock, in addition to the switch padlock, may be employed. An electric lock for a manually operable railway track switch is commonly controlled in part by traffic conditions adjacent the switch, and may also be controlled in part by manually operable means.

Some auxiliary tracks, such for example as industrial spur tracks, are provided with a derail adjacent the switch which connects the auxiliary track with a main track. The purpose of the derail is to prevent a car or train from moving off of the auxiliary track onto the main track when it is unsafe for such a movement to be made. The derail is therefore normally kept in the derailing position.

Some derails are mechanically connected with the associated switch, so that when the associated switch is moved to the reverse position for a traffic movement to or from an associated spur track, the derail will be operated at the same time to a reverse or non-derailing position. At some locations, however, such for example as at a street crossing, it would be difficult to install or maintain a mechanical connection for operating a derail on a spur track in conjunction with an associated switch.

In such instances, a derail for a spur track may therefore be operated by a separate lever, and may be provided with a circuit controller which shunts an adjacent section of the main track when the derail is in the non-derailing position. A signal which governs traffic movements over the same adjacent section of the main track would then be controlled to display a stop indication when the derail occupies its non-derailing position. Instead of shunting the adjacent track section, the circuit controller with which the derail is equipped may be arranged to open a signal control circuit directly when the derail is moved to the non-derailing position.

2

It has been found that, where a derail for a spur track is operable separately from an associated switch, trainmen, although they return the associated switch to its normal or main track position, sometimes forget to restore the derail to its derailing position after a train movement has been completed over the associated switch in the reverse position.

An object of my invention is the provision of means for preventing a derail, which is operable separately from an associated switch for an auxiliary track, from being inadvertently left in the non-derailing position when the associated switch is returned to the normal or main track position.

A feature of my invention for accomplishing this object is the provision of an electric lock arranged to lock the switch in the reverse position as well as in the normal position, a normal control circuit for the lock controlled by means including a normal switch contact which becomes closed in conjunction with an operation of the switch to its normal position, and a reverse control circuit for the lock controlled by means including a reverse switch contact, which becomes closed in conjunction with an operation of the switch to its reverse position, and including a normal derail contact which becomes closed in conjunction with an operation of the derail to its derailing position.

I shall describe one form of apparatus embodying my invention, and shall then point out the novel features thereof in claims.

The accompanying drawing is a diagrammatic view showing one form of apparatus embodying my invention, in which a stretch of main railway track *a—e* is connected with an auxiliary track *Z* by means of a track switch *A*, and in which a derail *D* for the auxiliary track is associated with switch *A*.

Similar reference characters refer to similar parts in the drawing.

Referring further to the drawing, the rails *1* and *1a* of the stretch of main railway track are divided by insulated joints *2* to form sections designated by the reference characters *1T*, *2T*, *3T*, and *4T*, respectively. Each of the track sections is provided with a track circuit including a suitable source of current, such for example as a battery *3*, connected across the rails adjacent one end of the section, and a track relay, designated by the reference character *R* preceded by the reference character for the corresponding section, connected across the rails adjacent the opposite end of the section.

A signal, designated by the reference character *S*, is located adjacent the end *e* of the stretch of main railway track. Signal *S* governs traffic movements over the stretch of main railway track from right to left, as shown in the drawing, which I shall assume is the westbound direction. Signal *S* may be of any suitable design, such for example as the well-known semaphore type or the search-light type. A control circuit for signal *S* includes contacts *4* and *5* of track relays *3TR* and *4TR*, respectively.

Switch *A* and derail *D* are operable by manual power applied through a switch operating lever *AV* and a derail operating lever *DV*, respectively, to a switch operating mechanism designated by the reference character *AW*, and a derail operating mechanism designated by the reference character *DW*, respectively. Each of the levers *AV* and *DV* has a normal position *n*, in which it is shown in the drawing, and a reverse position *r*.

Movement of lever *AV* to its *n* position effects movement of switch *A* to a normal or main track position, in which it is shown in the drawing, for traffic movements along the main track only. Movement of lever *AV* to its *r* position effects movement of switch *A* to a reverse position for traffic movements on the main track to or from the auxiliary track *Z*.

Movement of lever *DV* to its *n* position effects movement of derail *D* to a normal or derailing position, in which it is shown in the drawing. Movement of lever *DV* to its *r* position effects movement of derail *D* to a reverse or non-derailing position.

Switch *A* is provided with an electric lock, designated generally by the reference character *WL* and including latching mechanisms *13* and *14*. Electric switch lock *WL*

may be of any suitable design such, for example, as the type of electric lock disclosed and claimed in Letters Patent of the United States No. 2,387,115, granted October 16, 1945, to Herbert L. Bone for Electric Lock.

Switch lock WL includes a member, designated by the reference character P, which may be either a manually operable lever or a foot operable pedal mechanism. Member P has a normal position *n*, an intermediate position *c*, and a reverse position *r*. Member P is normally locked in its normal position *n* by a switch padlock. Member P is biased toward its intermediate position *c* by suitable means such, for example, as a spring 6, one end of which is attached to member P and the other end of which is secured to a fixed member 7. Spring 6 becomes compressed by movement of member P to its *n* position, and so, when member P is released by removal of the padlock, spring 6 moves member P to its intermediate position *c*.

Member P, upon being moved to its *c* position, moves a locking member 8 toward the right, as shown in the drawing. If further movement of member P toward its *r* position is then attempted, such further movement will be prevented by engagement of locking member 8 with a dog 9 until dog 9 has been lifted by an electromagnet 10 out of engagement with locking member 8.

A latch contact 11 is closed while member P is in its *n* position, but becomes opened when member P leaves its *n* position. A back contact 12 is closed when electromagnet 10 is deenergized, but becomes opened when electromagnet 10 becomes energized and lifts dog 9.

Through suitable latching mechanisms, designated by the reference characters 13 and 14, movement of lever AV from its *n* or its *r* position, respectively, is prevented by member P until member P is moved to its reverse position *r*.

The latching mechanisms 13 and 14 are linked to and controlled by the member P. Except when the member P is in its reverse position, the latching mechanisms will engage the switch lever AV locking it in either of its existing *n* or *r* positions and preventing movement of the switch lever. When member P is moved past its center position into its reverse position, the latching mechanisms are moved out of engagement with the switch lever. Switch lever AV is then free to be moved to another position. Thus it may be seen that switch lever AV cannot be operated from one position to another unless member P is first moved into its reverse position to disengage latching mechanisms 13 and 14 from the switch lever.

Operated in conjunction with derail D is a circuit controller, designated by the reference character DC, having contacts 15 and 16. Contact 15 is closed and contact 16 is open while derail D is in its normal position. When derail D is moved to its reverse position, contact 15 becomes opened and contact 16 becomes closed.

Operated in conjunction with switch A is a circuit controller, designated by the reference character AC, having contacts 17, 18, and 19. Contacts 18 and 19 are closed, and contact 17 is open, while switch A is in its normal position. When switch A is moved to its reverse position, contacts 18 and 19 become opened, and contact 17 becomes closed.

A normal switch repeater relay, designated by the reference character ANP, is energized while switch A is in its normal position while electromagnet 10 is deenergized and member P is in its *n* position.

Approach relays, designated by the reference characters WAR and EAR, are controlled by back contacts of relay ANP, and by traffic responsive relays such, for example, as track relays 1TR, 3TR, and 4TR, which are responsive to the presence of a train to the west or east, respectively, of switch A.

Having described, in general, the arrangement and control of the various parts of apparatus embodying my invention, I shall now describe the circuits and operation in detail.

As shown in the drawing, all parts of the apparatus are in the normal condition, that is, track sections 1T, 2T, 3T, and 4T are unoccupied, and therefore track relays 1TR, 2TR, 3TR, and 4TR are energized; switch A and derail D are in the normal position; signal S is displaying a proceed indication; levers AV and DV and member P are in their normal position *n*; electromagnet 10 and relays WAR and EAR are deenergized; and relay ANP is energized.

A circuit by which signal S is controlled to display a proceed indication passes from terminal B of a suitable

source of current, shown as a battery 2Q, and includes contacts 4 and 5 of relays 3TR and 4TR, respectively, mechanism of signal S, and terminal N of battery 2Q.

The circuit by which relay ANP is energized passes from terminal B, through contact 11 of member P, contact 12 of electromagnet 10, contact 19 of switch circuit controller AC, and the winding of relay ANP to terminal N.

I shall assume that, with apparatus embodying my invention, as shown in the accompanying drawing, a west-bound train passes signal S, deenergizing relay 4TR. With relay 4TR deenergized, contact 5 of relay 4TR opens the circuit for signal S, causing signal S to display a stop indication. The train, upon entering section 3T, deenergizes relay 3TR, causing contact 4 of relay 3TR to become opened, and thereby controls signal S to continue to display the stop indication.

I shall assume further that the train is to move onto auxiliary track Z. The train will therefore be stopped on section 2T, causing relay 2TR to be deenergized. With relay 2TR deenergized, a circuit is completed for energizing electromagnet 10, this circuit passing from terminal B, through the back point of contact 20 of relay 2TR, contact 18 of circuit controller AC, and the winding of electromagnet 10, to terminal N.

A trainman will then remove the padlock from member P, permitting member P to be moved by spring 6 to its intermediate position *c*. With electromagnet 10 energized, dog 9 will be lifted out of engagement with locking member 8, and therefore the trainman will move lever P to its *r* position. Member P, upon being moved to its *r* position, will remove latching devices 13 and 14 out of engaging positions with lever AV, thereby permitting lever AV to be moved from the *n* to the *r* position.

The trainman will then move lever AV to its *r* position, thereby moving switch mechanism AW to its reverse position for reversing switch A. The trainman will next permit member P to be returned to its *c* position, by spring 6. With switch A in its reverse position, contact 17 of circuit controller AC will be closed, and contacts 18 and 19 will be opened. The leverman will also move lever DV to its *r* position, thereby reversing derail D through mechanism DW. With derail D in its reverse position, contact 15 of circuit controller DC will be opened and contact 16 will be closed.

The train will then be moved onto track Z, after which the trainman will restore derail D to its normal position. Contact 15 of circuit controller DC will then again be closed, and contact 16 will be opened. With contact 15 of circuit controller DC now closed, and with contact 17 of circuit controller AC closed on account of switch A being in its reverse position, a circuit will be completed for energizing electromagnet 10, this circuit passing from terminal B, through contact 15 of circuit controller DC, contact 17 of circuit controller AC, and the winding of electromagnet 10, to terminal N.

Electromagnet 10, upon becoming energized, lifts dog 9 out of engagement with locking member 8, so that the trainman can now again move member P to its *r* position, thereby moving latch members 13 and 14 out of engaging positions with lever AV. The trainman will then return lever AV to its *n* position, thereby returning switch A to its normal position, through mechanism AW. The trainman will then again permit member P to be returned to its *c* position, by spring 6. The trainman will next return member P to its *n* position, and will apply the switch padlock, which will retain member P in its *n* position. All parts of the apparatus will now again be in the normal condition.

When the train is ready to leave siding Z, the trainman will remove the padlock from member P of switch lock WL, thereby permitting spring 6 to move member P to the intermediate position *c*. Further movement of member P toward its *r* position will then be prevented by engagement of locking member 8 with dog 9.

Member P, upon leaving its *n* position, however, opens latch contact 11, thereby deenergizing normal switch repeater relay ANP. With relay ANP deenergized, a circuit will be completed for energizing approach relay WAR, this circuit passing from the positive terminal of a battery 1Q, through a path including contact 24 of relay 1TR, back point of contact 25 of relay ANP, and the winding of relay WAR, back to battery 1Q. A circuit will also be completed for energizing approach relay EAR, this circuit passing from

the positive terminal of a battery 3Q, through a path which includes contact 27 of relay 4TR, contact 23 of relay 3TR, winding of relay 3AR, and back point of contact 26 of relay ANP, back to battery 3Q.

Electromagnet 10 will then be energized by a normal or first energizing circuit passing from terminal B, through the front point of contact 20 of relay 2TR, contacts 21 and 22 of relays WAR and EAR, respectively, contact 18 of circuit controller AC of switch A, and winding of electromagnet 10 to terminal N. Electromagnet 10, upon becoming energized, will lift dog 9 out of engagement with locking member 8.

The trainman will then move member P to its *r* position, thereby removing latching members 13 and 14 from the position for engaging lever AV. The trainman will then move lever AV from its *n* to its *r* position, thereby supplying power through switch operating mechanism AW for moving switch A from its normal to its reverse position. The trainman will then release member P, permitting spring 6 to return member P from its *r* position to its *c* position.

The trainman will next move lever DV from its *n* to its *r* position for transmitting power through derail operating mechanism DW for moving derail D to its reverse or non-derailing position. When derail D is moved to its reverse position, contact 15 of circuit controller DC will become opened and contact 16 will be closed.

I shall assume further that the train then leaves siding Z, and that a trainman forgets about derail D and tries to move member P to its *r* position for moving latching members 13 and 14 out of engaging positions with lever AV preparatory to moving lever AV back to its *n* position for restoring switch A to its normal position. With switch A in its reverse position, contact 17 of circuit controller AC for switch A will be closed, but with derail D in its reverse position, contact 15 of circuit controller DC for derail D will be open. Electromagnet 10 will therefore be deenergized, and dog 9 will engage locking member 8 and prevent the trainman from moving member P to its *r* position.

The trainman will therefore be reminded that he must return derail D to its normal position before he can return switch A to its normal position. He will therefore now move lever DV from its *r* to its *n* position, thereby restoring derail D to its normal or derailing position. Contact 15 of circuit controller DC will then be closed and contact 16 will be opened. Electromagnet 10 will then be energized by a second or reverse energizing circuit passing from terminal B, through contact 15 of circuit controller DC, as previously traced. Dog 9 will be lifted by magnet 10 out of engagement with locking member 8, and therefore the trainman will move member P to its *r* position, thereby moving latching members 13 and 14 out of engaging positions with lever AV, and will then move lever AV from its *r* position to its *n* position, thereby restoring switch A to its normal position. The trainman will then permit spring 6 to return member P to its *c* position, after which the trainman will move member P to its *n* position and apply the padlock for retaining member P in its *n* position.

When the train has moved off of the stretch of main track *a-e*, all parts of the apparatus will now again be in the normal condition.

It has been seen that, in apparatus embodying my invention, electromagnet 10 of switch lock WL is controlled by a second or reverse energizing circuit which includes a normal contact 15 of circuit controller DC for derail D. In this way, movement of member P to its *r* position for releasing lever AV, for returning switch A to its normal position, is prevented until after derail D has been returned to its normal position.

It follows that a trainman, upon attempting to return switch A from its reverse position to its normal or main track position, and finding it locked, will be reminded that he must first return derail D to its normal position. My invention therefore prevents derail D from being forgotten and left in its reverse or non-derailing position after switch A has been restored to its normal or main track position following a train movement over switch A in the reverse position.

When derail D is returned to its normal or derailing position, contact 16 will open a shunt path previously closed across the rails of track section 3T, permitting

relay 3TR to become energized when section 3T becomes unoccupied. Signal S will therefore be controlled to display a proceed indication when the other portions of the circuit which includes contact 4 of relay 3TR have also again become closed. If derail D could be forgotten and left in the non-derailing position, section 3T would remain shunted by the path which includes contact 16, so that relay 3TR would remain deenergized and signal S would continue to indicate stop and would therefore cause delay of a succeeding westbound train.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, an auxiliary railway track connected with a main railway track by a track switch, manually operable switch operating means for moving said switch between two extreme positions which comprise a normal or main track position for traffic movements along said main track and a reverse or auxiliary track position for traffic movements to or from said auxiliary track, a derail for said auxiliary track, manually operable derail operating means for moving said derail separately from said switch between two extreme positions which comprise a normal or derailing position and a reverse or non-derailing position, an electric lock for said switch, means controlled by said electric lock in the deenergized condition for rendering said manually operable switch operating means ineffective for moving said switch from either of its said extreme positions to the other, energizing means for energizing said electric lock controlled by means including said switch in the normal position, and other energizing means for energizing said electric lock controlled by means including said switch in the reverse position and said derail in the normal position.
2. In combination, an auxiliary railway track connected with a main railway track by a track switch, manually operable switch operating means for moving said switch between two extreme positions which comprise a normal or main track position for traffic movements along said main track and a reverse or auxiliary track position for traffic movements to or from said auxiliary track, a derail for said auxiliary track, manually operable derail operating means for moving said derail separately from said switch between two extreme positions which comprise a normal or derailing position and a reverse or non-derailing position, an electric lock for said switch, means controlled by said electric lock in the deenergized condition for rendering said manually operable switch operating means inoperable, energizing means for energizing said electric lock controlled by means including said switch in the normal position, and other energizing means for energizing said electric lock controlled by means including said switch in the reverse position and said derail in the normal position.
3. In combination, a main railway track, an auxiliary railway track, a track switch for interconnecting said main and auxiliary tracks, manually operable switch operating means movable to normal and reverse positions for effecting operation of said switch to normal and reverse positions respectively for traffic movements along said main track only when said switch is in said normal position or for traffic movements between said main and auxiliary tracks when said switch is in said reverse position, a derail for said auxiliary track having a normal or derailing position and a reverse or non-derailing position, manually operable derail operating means movable to a normal or a reverse position for effecting movement of said derail separately from said switch to its said normal and reverse positions respectively, traffic responsive means responsive to the presence of a train on said main track adjacent said switch, an electric lock for said switch, means controlled by said electric lock in its deenergized condition for rendering said manually operable switch operating means ineffective for effecting operation of said switch, energizing means for energizing said electric lock controlled by means including said traffic responsive means if there is no train on said main track adjacent said switch while said switch is in the normal position, and other energizing means for energizing said electric lock controlled by means including said derail

in its normal position while said switch is in the reverse position.

4. In combination, a main railway track, an auxiliary railway track, a track switch for interconnecting said main and auxiliary tracks, switch operating means for moving said switch to a normal position for traffic movements along said main track only and for moving said switch to a reverse position for traffic movements over said main track to or from said auxiliary track, a derail for said auxiliary track, derail operating means for moving said derail separately from said switch to a normal or derailing position and for moving said derail to a reverse or non-derailing position, an electric lock for said switch, means controlled by said electric lock in its deenergized condition for rendering said switch operating means ineffective for moving said switch to either its normal position or its reverse position, traffic responsive means responsive to traffic movements over said main track adjacent said switch, a first energizing circuit for said electric lock controlled by means including said traffic responsive means for energizing said electric lock if there is no train on said main track adjacent said switch while said switch is in the normal position, and a second energizing circuit for said electric lock controlled by means including said derail in the normal position for energizing said electric lock while said switch is in the reverse position.

5. In a railway traffic controlling system for a stretch of main railway track which is connected with an auxiliary track by a railway track switch, in which said auxiliary track is equipped with a derail adjacent said switch, in which said main track is equipped with traffic responsive means and with a signal for governing traffic movements over said switch, in which said switch is provided with switch operating means for at times moving said switch to a normal position for traffic movements along said main track only and for at other times moving said switch to a reverse position for traffic movements on said main track to or from said auxiliary track, and in which said derail is provided with derail operating means for at times moving said derail separately from said switch to a normal or derailing position and for at other times moving said derail to a reverse or non-derailing position, the combination comprising, an electric switch lock, means controlled by said electric switch lock in the deenergized condition for rendering said switch operating means ineffective to move said switch to either the normal or the reverse position, a first control circuit for said switch lock controlled by means including said traffic responsive means for energizing said switch lock if there is no train on said main track adjacent said switch while said switch is in the normal position, a normal contact and a reverse contact operated in conjunction with said derail and arranged to be closed while said derail is in its normal or its reverse position respectively, a second control circuit for said switch lock controlled by means including said normal contact, and means including said reverse contact upon becoming closed for controlling said signal to display a stop indication.

6. In a railway traffic controlling system for a stretch of main railway track which is connected with an auxiliary track by a railway track switch, in which said auxiliary track is equipped with a derail adjacent said switch, in which said main track is equipped with traffic responsive

means and with a signal for governing traffic movements over said switch, in which said switch is provided with switch operating means for at times moving said switch to a normal position for traffic movements along said main track only and for at other times moving said switch to a reverse position for traffic movements on said main track to or from said auxiliary track, and in which said derail is provided with derail operating means for at times moving said derail separately from said switch to a normal or derailing position and for at other times moving said derail to a reverse or non-derailing position, the combination comprising, an electric switch lock, means controlled by said electric switch lock in the energized condition for enabling said switch operating means to move said switch but controlled by said electric switch lock in the deenergized condition for rendering said switch operating means inoperative, control means for said switch lock controlled by means including said traffic responsive means for energizing said switch lock if there is no train on said main track adjacent said switch while said switch is in the normal position, other control means for said switch lock controlled by means including said derail in the normal position, and means including said traffic responsive means and said derail for controlling said signal to display a proceed indication if said main track is unoccupied adjacent said switch and only if said derail is in a derailing position.

7. In railway traffic controlling means for a stretch of main railway track which is connected with an auxiliary track by a track switch, in which said auxiliary track is equipped with a derail adjacent said switch, in which said switch is provided with switch operating means for at times moving said switch to a normal position for traffic movements along said main track only and for at other times moving said switch to a reverse position for traffic movements on said main track to or from said auxiliary track, and in which said derail is provided with derail operating means for at times moving said derail separately from said switch to a normal or derailing position and for at other times moving said derail to a reverse or non-derailing position, the combination comprising, an electric switch lock, means controlled by said electric switch lock in the energized condition for enabling said switch operating means to move said switch but controlled by said electric switch lock in the deenergized condition for rendering said switch operating means ineffective to move said switch, energizing means for said switch lock controlled by means including said switch in its normal position, and other energizing means for said switch lock controlled by means including said derail in the normal position.
